AMUSEMENT MACHINE

Harry H. Hoke, Jr., Washington, D. C.

Application January 11, 1935, Serial No. 1,397

24 Claims. (Cl. 273—95)

The invention relates to an amusement machine and more especially to a coin controlled target practice device.

The primary object of the invention is the provision of a machine or device of this character wherein, through the intermediary of a pistol, target practice may be had and by accuracy of shots in hitting a group of targets the mechanism of the machine or device is set so that a prize will be dispensed to the successful scoring by a shooter, the machine or device being controlled by the deposit of a coin of proper denomination in the pistol, so that the latter can be operated for the actuation of the machine under a successful scoring.

Another object of the invention is the provision of a machine or device of this character, wherein contestants will be permitted to make a selection of a prize winning and if a perfect score by the shooting of the pistol is attained the selected prize will be awarded such scorer or winner, the mechanism of the machine or device being so constructed and arranged that it will be impossible for a duplication of an award or prize under a single scoring, the pistol or shooter being rendered operative by the deposit of a coin therein so that a scoring may be had under the firing of the pistol or shooter and only an award will be made when a complete score has been made, otherwise the machine is passive and no award will be had.

A further object of the invention is the provision of a machine or device of this character, wherein a contestant is enabled to practice accuracy in shooting in that a complete score must be obtained on a target before an award is had from the machine, thus amusement being afforded in addition to the practice characteristic of the machine.

A still further object of the invention is the provision of a machine or device of this character, wherein but a single award of a selective prize by a contestant is issued by the machine and this is only had through a complete scoring in the shooting of the pistol and the striking of the target by a determined number of shots, as for example, five strikes or hits of such target.

A still further object of the invention is the provision of a machine or device of this character, wherein the prizes are on display and any one of these can be selected by a contestant and such award of the selected prize can be only attained by a complete scoring on a target by the shooting of the pistol and such pistol is rendered operative by a coin when deposited therein.

A still further object of the invention is the pro-

vision of a machine or device of this character, which is comparatively simple in its construction, thoroughly reliable and efficient in its operation, incapable of fraudulent or illegitimate operation, requiring skill by an operator, awarding a prize to a successful operator or winner, neat in appearance, attractive and lending amusement to the operator, and inexpensive to manufacture.

With these and other objects in view, the invention consists in the features of construction, combination and arrangement of parts as will be hereinafter more fully described in detail, illustrated in the accompanying drawings, which disclose the preferred embodiment of the invention, and pointed out in the claims hereunto appended.

In the accompanying drawings:

Figure 1 is a fragmentary perspective view of a machine or device constructed in accordance with the invention.

Figure 2 is a fragmentary central vertical sectional view through the machine.

Figure 3 is a fragmentary front elevation approximately midway of the transverse center of said machine, showing in elevation the prize pockets or racks and the target.

Figure 4 is a fragmentary rear elevation looking toward the rear of the prize pockets or racks and showing by full lines the locked position of certain of the dispensing bottoms or doors of the prize pockets or racks and by dotted lines a selected one of the bottoms or doors released and open.

Figure 5 is a sectional view on the line 5—5 of Figure 2 and on an enlarged scale.

Figure 6 is a fragmentary sectional view on the line 6—6 of Figure 2 looking in the direction of the arrows.

Figure 7 is a view similar to Figure 6 showing the parts therein in a shifted position.

Figure 8 is a fragmentary elevation of certain of the parts as shown in Figure 3 and in a shifted position.

Figure 9 is a fragmentary rear elevation of the target and its adjuncts.

Figure 10 is a vertical sectional view showing the target and adjuncts in end elevation.

Figure 11 is a perspective view of the lock bar in association with the target.

Figure 12 is a fragmentary vertical sectional view through the machine, showing the pistol in side elevation.

Figure 13 is a sectional view on the line 13—13 of Figure 9.

Similar reference characters indicate corre-

sponding parts throughout the several views in the drawings.

Referring to the drawings in detail, the machine or device comprises a casing A having 5 in its upper portion and fore thereof a shooting gallery 10 and aft thereof prize pockets or racks 11, these being arranged in transverse rows and set with glass partitions 12 to make visible prizes deposited therein, there being a riser 13 between 10 the gallery 10 and the pockets or racks 11, as such pockets or racks are in elevation to the flooring 14 of the gallery. The sides and front of the upper portion of the casing A are fitted 15 with glass panels 15, 16 and 17, respectively, the panels 15 being permanent, while the panels 16 are carried by side bars 18, hinged at 19 for opening and closing movements and when open access is had to the pockets or racks 11 for the placement of prizes therein. It is preferable 20 to have each door carry a key operated lock 20 to fasten the same closed. The panel 17 is carried by a front door 21, hinged at 22 for vertical swinging movement and provided with end locks 23 for fastening said door 21 closed. This door, 25 when open, affords access to the gallery 10.

At the front of the casing A is fixedly mounted a turret plate 24 in which is swiveled a coin controlled pistol or shooter 25, the details of which constitute the subject matter of Letters Patent 1,551,858, dated September 1, 1925, and its coin chute 26 delivers a coin of a predetermined denomination into the pistol for rendering the same operative, it having the trigger 27 for its firing mechanism to project a bullet therefrom 30 into the gallery 10. This deposit of a coin within the chute 26 frees a hand operable slide 28 which normally is locked against actuation for the projecting of a plunger 29 for a purpose presently described.

40 Fitted in the riser 13, preferably centrally located in the casing A, is a target including a face plate 30 having targets 31 arranged in series, preferably five in number, and these gradually decreasing in size through exposure through 45 bull's-eyes 32, the targets 31 at their exposure faces being preferably black and carried on upright leaf springs 33 mounted at their lower ends by fasteners 34 to a supporting rail 35 fixed at the rear of the plate 30 to have the targets 50 31 yieldably confront the respective bull's-eyes 32 to be struck by a bullet as may be spent by the pistol 25.

Above the bull's-eyes 32 in the plate 30 is a series of scoring openings 36 for exposing scoring 55 slides 37 adapted for vertical movement in guides 38. These slides on their faces for exposure through the scoring openings 36 bear colors of hues distinguished from each other and are visible on a scoring through said scoring 60 openings 36. The slides have connected to their rear sides coiled retractile springs 39, these being also fixed at the lower portion of the plate 30 and functioning to lower the slides for the exposure of their colored faces through the scoring 65 openings 36 when the said slides are released under a strike of the respective targets 31. The springs 39 carrying the targets 31 at their upper ends are provided with latching pins 40 for the said slides 37 to engage the lower ends of these 70 to hold the same elevated when the targets 31 are in normal or neutral exposed position, and in this elevated relation of the slides 37 the scoring openings 36 are blank, that is to say, the colored faces upon the slides 37 are not exposed 75 therethrough and such exposure is only made

when a target has been struck of a companion to a particular slide so as to indicate a score or a strike of a target.

Rearwardly of the plate 30 is a resetting bar 41 carried upon a lifter arm 42 supported upon guides 43, the arm being slotted, at 44, to receive said guides 43, and the lower end of this arm 42 aligns with a guiding eye 45 which depends beneath the floor 14 of the gallery 10 to receive a lifter shoe 46 carried by a push rod 47 supported in a guide 48 depending from a sub-floor board 49 fixed in the casing A. This bar 41 acts against the parts carried by the slides 37 to lift the latter in unison with each other when in lowered positions. This rod 47 at its forward end carries a head 50 which at all times is in the path of movement of the plunger 29 of the pistol 25 irrespective of the swivel action of the latter, so that the said rod 47 can move rearwardly. The shoe 46 will play upon the lifter arm 42 for the raising of the lifter bar 41 which elevates one or all of the scoring slides 37 when the same have been dropped or lowered by the springs 39 and the release by the leaf springs 33.

25 The shoe 46 has connected with it a coiled tensioning spring 51 which is also fixed to the floor piece 49 to urge the rod 47 forwardly, or, in other words, effects a retrieving of the said rod 47 after the shifting rearwardly thereof. 30 Also, the shoe 46 has pivotally connected thereto a link 52 which is pivoted at 53 to a toothed segment or ratchet member 54 journaled at 55 on a bracket 56 depending from the floor board 49. This segment or member 54 has its teeth 57 engaged by a double acting latching dog 58, pivoted at 59 for reverse swinging movement and held in engagement with the teeth by a spring 60. The purpose of the segment or member 54 is to allow successive latching of the rod 47 when 40 moved rearwardly from retrieving or retrograde movement until the dog 58 has traversed the full number of teeth 57 of such segment or member 54, whence the rod 47 will be automatically shifted forwardly under the action of the spring 59. It 45 will be seen that at any intermediate point of movement of the rod 47 from its normal forward position the said rod cannot retrieve or shift to the front of the machine and this stalls a duplicating operation of the machine. In other words, 50 this segment or member 54 is a safety latch for the rod 47.

The pistol 25 is built with a bullet retrieving cup 61 and the floor 14 is constructed as a chute and arranged at an angle to deliver the 55 bullets when fired by the pistol in the direction of the target to the cup 61, whence these bullets, under the mechanism of the pistol, load the same and are placed for the firing of the same through the muzzle 62 of said pistol by manual actuation of the trigger 27. The aiming of the pistol 25 is the conventional way for firing at the target and for accuracy in making a hit.

Rearwardly of the riser 13 and within the casing A is a vertically disposed supporting plate 63, 65 while beneath the pockets or racks 11 are transversely disposed spaced parallel bars 64 which pivotally support releasing arms 65, these being pivoted at 66 and normally disposed to hold the bottoms 67 of the pockets or racks 11 closed or 70 in supporting position for prizes as contained within said pockets or racks.

The arms 65 in their series, through linkage 68, pivoted at 69 and 70, respectively, thereto, are connected to bolts 71, these being slidably fitted 75

in an arcuate-shaped guide plate 72, so that the bolts 71 are disposed in a radial direction from a common central point. The plate 72 is carried by the supporting plate 63. At one side of the casing A is arranged a series of cranked shafts 73, these being properly journaled in bearings 74, and to their cranks 75 are loosely connected links 76 which are also connected to certain of the bolts 71, as the remaining bolts have the direct linkage with the arms 65. Through this linkage motion is imparted to the arms 65 for the throwing of the same to a position for the opening of the doors or bottoms 67 to the pockets or racks 11 or the closing thereof, the bolts 71 being operated in a manner presently described. Shiftable and swingingly supported is a trigger 77, it playing through a guide 78 on said plate 63 and carrying a nose 79 adapted for alignment selectively with any one of the bolts 71. The trigger 77 has connected therewith a tensioning spring 80, it being also fixed to the casing A for exertion of tension upon said trigger to retract the same from the bolts 71, which is the normal position thereof.

Pivotedly connected to the trigger 77 and to the plate 63 is a setting toggle leverage 81, one of its parts having pivoted, at 82, a link 83, this being concentrically pivoted, at 84, to a shifting segment 85, its arbor 86 being constituted by a turning shaft 87, the same being formed with a hub 88 carrying said segment 85. This turning shaft 87 extends through the front of the casing A and carries a hand knobbed dial 89, the knob being indicated at 90, and such dial has degree markings 91 thereon following the periphery of the same for coaction with a pointer 92 provided on the front of the casing A and by manually turning such dial 89 under selective degree markings thereof the segment 85 will throw the trigger 77, which has a shifting movement, for bringing the nose 79 thereof into alignment with a determined bolt 71, so that when the trigger 77 is moved in a manner presently described, a selected prize as contained within a pocket or rack 11 can be dispensed or delivered from the machine.

Directly above the dial 89 at the front of the casing A is a handle 93 carried by a releasing latch rod 94, it being slidable in a barrel 95 fitted within the casing and normally projected into a selected keeper hole 96 of a series in the segment 85, so that the latter can be locked thereby and is releasable on pulling outwardly upon the handle 93, which moves the latching rod 94 to releasing position. Surrounding this rod 94 is a coiled tensioning spring 96, it playing against an abutment 98 and being fixed relative to the barrel 95, so that the rod 94 is urged into latching position with the segment 85 for normally locking the same.

Located at the front of the casing A above the handle 93 is a turning knob 99 which is on a rotatable throw shaft 100 suitably journaled in the plate 63 and casing A. This throw shaft 100 has a crank 101 to which is pivoted a link 102, the same being also pivoted to an extension 103 of a lock bar 104 which is slidable on the plate 63 directly rearwardly of the target plate 30, the plate 63 being cut away, at 105, for the projecting of a notched locking rack 106 carried by the said bar 104 for presenting the said rack 106 to the keeper pins 107 on the slides 37, the springs 39 being connected to these keeper pins 107, and when these slides 37 are in their full elevated position or raised, the keeper pins 107 engage in

the notches 108 in the rack 106 and thus this bar 104 is locked against movement, it being required that before the bar 104 can have movement, all of the pins 107 will have been freed from the notches 108 in the rack 106. These slides 37 are lowered when a bullet from the pistol 25 strikes the target 31. It will be apparent that before the lock bar 104 can be shifted, the rack 106 must be released by having the pins 107 released from the notches 108 therein in the series of scoring slides 37. The bar 104 at the extension 103 carries the trigger 77, this being pivoted to said extension so that when the bar is shifted the trigger will move therewith and also the said trigger is susceptible of arcuate swinging movement.

On the shaft 100 is carried a locking wheel 109, it being provided with the spaced lugs 110 and 111, respectively, peripherally arranged thereon for play upon a rocking lock lever 112 pivoted, at 113, to a bracket 114 stationarily mounted and formed with a tripping extension 115 at the end remote from the wheel 109 and arranged in confronting relation to the guide eye 45 to be acted upon by the shoe 46, so that when the shoe moves rearwardly, engagement thereof is had with the extension 115, causing the lever 112 to tilt for releasing it from the lugs 110 and 111 for the unlocking of the said wheel to allow the turning of the knob 99. The turning of the knob 99 causes the shifting of the trigger 77 for action upon a confronting bolt 71. It is, of course, understood that the turning of the shaft 100 enables the dispensing or release of the contents of one of the pockets or racks 11 and this shaft 100 when freed for turning is manually operated. On the shaft 87 is a peripherally notched safety wheel 116, the peripheral notches 117 therein being congruous with the identifying indicia, as at 118, of the respective pockets or racks 11 and under selective setting of the dial 91 a notch 117 is presented for engagement with a latching dog 119 pivoted at 120 and tensioned by a spring 121. This dog 119 has association with a control slide 122 which in its order of arrangement is hung with one of the scoring slides 37 so that when that target 31 releases the said slide with which the control slide 122 is associated permits, through the instrumentality of the link 123, the dog to drop, which by so doing will engage in the notch 117 in the safety wheel 116 and thereby locking the shaft 87 against rotation so that it is impossible to further alter a further selection of pocket or rack prize release.

The lever 112 has connected therewith on that portion to one side of its pivot 113 next to the eye 45 a spring 124 which holds the extension 115 in lowered confronting relation to the path of movement of the shoe 46. Interiorly of the casing A and depending from its top is an electric lamp 125, it being arranged in a switch controlled circuit (not shown) and adapted, when illuminated, to give light to the shooting gallery 10 and to the prize pockets or racks 11, respectively.

Immediately forwardly of the arrangement of the pockets or racks 11 and dividing the gallery 10 from such pockets or racks is a glass pane or window 126 which does not interfere with vision 70 for inspection of the contents of the pockets or racks 11 but at the same time avoids any possibility of access to these pockets or racks should entry be gained to the gallery 10.

The bottoms or doors 67 for the respective 75

pockets or racks 11 are preferably supported by hinges 127 so that they will have vertical swinging movement from closing to open position and vice versa.

5 The coin deposited in the pistol 25 is freed therefrom into a chute 128 which delivers such coin into a tray, box or the like 129 which is the depository therefor.

Below the pockets or racks 11 is a delivery chute 130, it being inclined in a forward direction and accessible through a delivery window or opening 131 as provided at the front of the casing A of the machine or device and the prizes as won by a contestant are obtainable therethrough.

15 In the operation of the machine it is assumed that the pockets or racks 11 have contents in the nature of prizes and a person being desirous of winning a selected content of one of the pockets or racks 11 is required to deposit the proper coin 20 in the chute 26 of the pistol 25. In so doing the firing mechanism is put in order for the shooting of the pistol. Then it is required that the slide 28 which is released for actuation be moved, causing the plunger 29 to shift the rod

25 47, moving the shoe 46 which acts upon the extension 115 of the safety lever 112 which normally locks the wheel 109. Thereupon the person turns the dial 89 so that the scale marks 91, by a selected one thereof, can be brought to alignment with the pointer 92, but before the dial 89 can be turned the person must pull outwardly upon the handle 93 which retracts the rod 94, releasing the segment 85, and by the turning of the dial under the selected scale mark which is congruous with a selected pocket or rack 11 for a determined prize as contained therein, the said segment will cause the shifting of the slide 77, setting its nose 79 aligned with the bolt 71 linked with the release arm 65, permitting the door 67 to become open to that particular pocket or rack.

40 However, the slide 77, while susceptible of having its nose 79 align with the bolt 71 as before mentioned, will be prevented from shifting movement by the lock bar 104, because the rack 106 thereof is locked with the keeper pins 107 of the scoring slides 37 which are normally in raised position. Now, on actuating the trigger 27 of the pistol, a bullet is sent through the muzzle 62 to the target and by this bullet striking a target 31 45 the same will release the slide 27 companion thereto, it being required that before the lock bar 104 can be moved all of the targets 31 must be struck by a bullet and concurrently the lowering of all of the scoring slides 37, these indicating a full 50 score or a completed score through the scoring openings 38. By turning the knob 99 an arm 65 will be moved to releasing position for the opening of the door or bottom 67 of the selected pocket or rack 11 and freeing its contents which will be 55 delivered by the chute 130 to the window or opening 131 for the acquiring thereof by the successful scorer.

60 On the delivery of the contents of the particular pocket or rack 11, the lever 112 will have locked the wheel 109 and also the dog 119 will have locked the wheel 116, so that the shafts carrying these wheels 109 and 116 cannot be turned by the knobs 90 and 99, respectively, and thus the machine is so locked until another deposit of a coin is made in the chute 26 of the pistol 25, whereupon the wheel 109 is freed from being locked by the release of the lever 112 from said wheel 109 and by the release of the dog 119 from the wheel 116, it being understood, of course, that the shoe 46 actuates the said lever

112 for the freeing of said wheel 109 and also is effective for the resetting of the targets 31 and the scoring slides 37. The lever 112 at the beginning of the play will lock the shaft 100 against turning movement as this shaft is freed for turning at the end of the play. The machine then is in a reset condition, it being understood, of course, that the resetting is effected by actuating the slide 28 of the pistol 25 and by the shooting of the shooter or pistol 25 and further scoring can 10 be attained in the use of the machine.

15 It should be obvious that there cannot be delivered a prize from the machine or device except by the striking of all of the series of targets 31, otherwise no delivery of a prize can be had.

At an interim after the firing of the first shot of the pistol 25 and before a striking of the target 31 associated with the control slide 122, the dial 89 may be turned for an altering of the selection of a prize winning constituting the content of a determined pocket or rack 11. In other words, should the contestant first conclude to have a winning from one pocket or rack 11 and before completion of the firing period his mind be changed as to the selection, he can, by manipulation of the dial 89 under changing of the scale 91, set the machine for the delivery of a prize as contained in any one of the other pockets or racks 11 as may be decided upon by him and by a complete scoring the finally selected prize will be 30 delivered to the contestant.

What is claimed is:

1. A machine of the character described comprising a shooting gallery, prize racks connected to said gallery and having delivery means for 35 each rack, mechanism arranged to hold the delivery means selectively releasable, a plurality of resetting targets located in said gallery, locking means releasable on the striking of all of the targets and connected to said mechanism for rendering the same operative, manually operated mechanism for operating said holding mechanism, manually operated means for setting said holding mechanism for the actuation of a selected delivery means, a pistol arranged for firing 40 action in the gallery and having a range in the direction of the targets, means controlled by said pistol for the resetting of the targets after being struck, and means compelling the resetting means to complete its movement before returning 50 to initial position.

2. A machine of the character described comprising a shooting gallery, prize racks connected to said gallery and having delivery means for each rack, mechanism arranged to hold the delivery means selectively releasable, a plurality of resetting targets located in said gallery, locking means releasable on the striking of all of the targets and connected to said mechanism for rendering the same operative, manually operated 55 mechanism for operating said holding mechanism, manually operated means for setting said holding mechanism for the actuation of a selected delivery means, a pistol arranged for firing action in the gallery and having a range in the 60 direction of the targets, means controlled by said pistol for the resetting of the targets after being struck, means compelling the resetting means to complete its movement before returning to 65 initial position, and hand releasable latching 70 means for the first-named mechanism.

3. A machine of the character described comprising a shooting gallery, prize racks connected to said gallery and having delivery means for each rack, mechanism arranged to hold the delivery 75 means for the first-named mechanism.

ery means selectively releasable, a plurality of resetting targets located in said gallery, locking means releasable on the striking of all of the targets and connected to said mechanism for rendering the same operative, manually operated mechanism for operating said holding mechanism, manually operated means for setting said holding mechanism for the actuation of a selected delivery means, a pistol arranged for firing action in the gallery and having a range in the direction of the targets, means controlled by said pistol for the resetting of the targets after being struck, means compelling the resetting means to complete its movement before returning to initial position, hand releasable latching means for the first-named mechanism, and means automatically locking the manually operated means and controlled by one of the targets.

4. A machine of the character described comprising a shooting gallery, prize racks connected to said gallery and having delivery means for each rack, mechanism arranged to hold the delivery means selectively releasable, a plurality of resetting targets located in said gallery, locking means releasable on the striking of all of the targets and connected to said mechanism for rendering the same operative, manually operated mechanism for operating said holding mechanism, manually operated means for setting said holding mechanism for the actuation of a selected delivery means, a pistol arranged for firing action in the gallery and having a range in the direction of the targets, means controlled by said pistol for the resetting of the targets after being struck, means compelling the resetting means to complete its movement before returning to initial position, hand releasable latching means for the first-named mechanism, means automatically locking the manually operated means and controlled by one of the targets, and means coacting with the manually operated mechanism to automatically lock the same after actuation thereof.

5. A machine of the character described comprising a shooting gallery, prize racks connected to said gallery and having delivery means for each rack, mechanism arranged to hold the delivery means selectively releasable, a plurality of resetting targets located in said gallery, locking means releasable on the striking of all of the targets and connected to said mechanism for rendering the same operative, manually operated mechanism for operating said holding mechanism, manually operated means for setting said holding mechanism for the actuation of a selected delivery means, a pistol arranged for firing action in the gallery and having a range in the direction of the targets, means controlled by said pistol for the resetting of the targets after being struck, means compelling the resetting means to complete its movement before returning to initial position, hand releasable latching means for the first-named mechanism, means automatically locking the manually operated means and controlled by one of the targets, and means coacting with the manually operated mechanism to automatically lock the same after actuation thereof and released by said pistol controlled means for the resetting of the targets.

70 6. A machine of the character described comprising a shooting gallery, prize racks connected to said gallery and having delivery means for each rack, mechanism arranged to hold the delivery means selectively releasable, a plurality of resetting targets located in said gallery, locking means

releasable on the striking of all of the targets and connected to said mechanism for rendering the same operative, manually operated mechanism for operating said holding mechanism, manually operated means for setting said holding mechanism for the actuation of a selected delivery means, a pistol arranged for firing action in the gallery and having a range in the direction of the targets, means controlled by said pistol for the resetting of the targets after being struck, means compelling the resetting means to complete its movement before returning to initial position, hand releasable latching means for the first-named mechanism, means automatically locking the manually operated means and controlled by one of the targets, 15 means coacting with the manually operated mechanism to automatically lock the same after actuation thereof and released by said piston controlled means for the resetting of the targets, and scoring indicators cooperating with the targets. 20

7. A machine of the character described comprising a shooting gallery, prize racks connected to said gallery and having delivery means for each rack, mechanism arranged to hold the delivery means selectively releasable, a plurality of resetting targets located in said gallery, locking means releasable on the striking of all of the targets and connected to said mechanism for rendering the same operative, manually operated mechanism for operating said holding mechanism, 25 manually operated means for setting said holding mechanism for the actuation of a selected delivery means, a pistol arranged for firing action in the gallery and having a range in the direction of the targets, means controlled by said pistol for the resetting of the targets after being struck, means compelling the resetting means to complete its movement before returning to initial position, hand releasable latching means for the first-named mechanism, means automatically locking 30 the manually operated means and controlled by one of the targets, and means coacting with the manually operated mechanism to automatically lock the same after actuation thereof and released by said pistol controlled means for the resetting of the targets, 35 for the resetting of the targets after being struck, means compelling the resetting means to complete its movement before returning to initial position, hand releasable latching means for the first-named mechanism, means automatically locking 40 the manually operated means and controlled by one of the targets, means coacting with the manually operated mechanism to automatically lock the same after actuation thereof and released by said pistol controlled means for the resetting of the targets, and scoring indicators cooperating with the targets and automatically reset on the resetting of the targets.

8. A machine of the character described, a selective prize award carrier, mechanism for selectively releasing a prize from said carrier, a target having a series of striking portions and mechanism operating for releasing said first-named mechanism on the hitting of the complete series of striking portions of the target to 55 liberate the prize from the carrier.

9. A machine of the character described, comprising a prize award carrier, mechanism for the carrier, means for manually setting said mechanism for selective award of a prize therefrom, a 60 target having a plurality of striking portions and means for holding the first-named mechanism against action and operative upon completing the hitting of the plurality of striking portions of said target. 65

10. A machine of the character described, comprising a prize award carrier, mechanism for the carrier, means for manually setting said mechanism for selective award of a prize therefrom, a 70 target having a plurality of striking portions, means for holding the first-named mechanism against action and operative upon completing the hitting of the plurality of striking portions of said target and means for locking the last-named 75

striking portion hit, means rendering the prize, when released, accessible to the player, a gallery for the prize award carrier and the target, manually operated means for the setting of the first-named mechanism, a coin controlled mechanism for effecting the automatic resetting of the striking portions of the target and operated on rendering the shooter operative and means for collecting shooting missiles delivered to the target and returning the same to the shooter.

19. A machine of the character described, a target having a plurality of striking portions, a prize award carrier and mechanism controlled by the striking portions and rendered operative on the hitting of the entire number of striking portions of the target for the release of the carrier for a selective award of a prize therefrom.

20. A machine of the character described, a target having a plurality of striking portions, a prize award carrier, mechanism controlled by the striking portions and rendered operative on the hitting of the entire number of striking portions of the target for the release of the carrier for a selective award of a prize therefrom and a shooter for effecting the hitting of the striking portions of said target.

21. A machine of the character described comprising a shooting gallery, prize racks connected to said gallery and having delivery means for each rack, mechanism arranged for holding the delivery means selectively releasable, a plurality of targets located in said gallery, locking means releasable on the striking of all the targets and connected to said mechanism for rendering the same operative to release a prize and manually operated mechanism for moving said holding means to release position.

22. A machine of the character described comprising a shooting gallery, prize racks connected to said gallery and having delivery means for each rack, mechanism arranged for holding the delivery means selectively releasable, a plural-

ity of targets located in said gallery, locking means releasable on the striking of all the targets and connected to said mechanism for rendering the same operative to release a prize, manually operated mechanism for moving said holding means to release position and manually operated means for setting said holding mechanism for the actuation of a selected delivery means.

23. A machine of the character described comprising a shooting gallery, prize racks connected to said gallery and having delivery means for each rack, mechanism arranged for holding the delivery means selectively releasable, a plurality of targets located in said gallery, locking means releasable on the striking of all the targets and connected to said mechanism for rendering the same operative to release a prize, manually operated mechanism for moving said holding means to release position, manually operated means for setting said holding mechanism for the actuation of a selected delivery means and a pistol arranged for firing action in the gallery and having a range in the direction of the targets.

24. A machine of the character described comprising a shooting gallery, prize racks connected to said gallery and having delivery means for each rack, mechanism arranged for holding the delivery means selectively releasable, a plurality of targets located in said gallery, locking means releasable on the striking of all the targets and connected to said mechanism for rendering the same operative to release a prize, manually operated mechanism for moving said holding means to release position, manually operated means for setting said holding mechanism for the actuation of a selected delivery means, a pistol arranged for firing action in the gallery and having a range in the direction of the targets and means controlled by said pistol for the resetting of the targets after being struck.
